UNITED STATES PATENT OFFICE.

FERDINAND E. FORSTER, OF NEW YORK, N. Y.

THREAD-MOSAIC.

SPECIFICATION forming part of Letters Patent No. 284,406, dated September 4, 1883.

Application filed December 19, 1882. (No model.)

To all whom it may concern:

Be it known that I, FERDINAND E. FORSTER, of New York city, in the county and State of New York, have invented certain new and useful Improvements relating to Thread-Mosaics, of which the following is a specification.

I designate as "thread-mosaics" ornaments of worsted or other threads produced by stretching yarns or threads in the form of a more or less firm bunch or rope, bound around and cut off in short lengths. The yarns are of different colors, and so arranged as to present ornamental figures on the cut ends.

The invention relates to means for facilitating the manufacture of such ornaments. I provide a sufficient number of threads or yarns—white, black, and of various hues and shades, according to the figure to be produced. These being mounted each on a separate spool or other carrying device, so as to require a moderate tension to draw off the several yarns, they are threaded separately through holes in four perforated plates in the required order, and a weight attached to each separately. For the succeeding operation the plates are held in parallel planes, the extremes of the series at a considerable distance apart and the two intermediate plates close together, about half way between the two outer plates. I will describe the plates as held horizontally one above the other, and I prefer for obvious reasons to so hold them. Thus conditioned, a smooth string or wire is passed lightly around the series and a gentle tension put on it, tending to draw the several yarns together. Then the two middle plates are moved steadily apart, the uppermost being moved up nearly or quite into contact with the upper and the other being moved down nearly or quite into contact with the lower plate. At the same time the encircling wire is tightened gradually, and when the movement is complete the thread will be tightly tied together in a small solid bunch in the middle, the yarns converging thereto from the perforated plates both below and above. Then a smooth ring or circular yoke with a smooth interior is applied in two halves, one from each side, and united to form a small ring just sufficient to hold the yarns nearly or quite in contact. This is applied at the point in the middle where the yarns have

been tightly bunched together, and is moved gradually upward and downward, correspondingly drawing the converging yarns together. While this movement is progressing the yarns are tied firmly at short distances apart by hand or machinery. After the greater portion of the length between the two outer plates has been thus tied together, the portions of threads thus bunched and tied may be drawn outward and tied by hand or machinery, the several yarns being drawn through the perforations in the two upper plates, and thereby kept rigidly in the proper order. After a yard or two has been thus drawn down, the ring is again moved upward, either steadily or intermittently, and the tying at short intervals continued. When this has proceeded so far as to become inconvenient, the compacted portion may be again drawn down, and the yarns again further being delivered through the several spools and drawn down through the several plates, all the time maintaining the proper order. Thus the work may continue indefinitely, or so long as the several yarns hold out. When a spool is exhausted, the attendant may tie onto the end or otherwise attach a fresh yarn of the same color, and the work may continue. The rope or extended firm collection of the yarns is cut up into short lengths, either while this operation of tying is going on or at some subsequent period, thus producing a great number of small rosettes or ornaments, which may be cemented or otherwise attached in any desired position on carriage-linings or other article which it is intended to decorate.

The accompanying drawings form a part of this specification, and represent what I consider the best means of carrying out the invention.

Figure 1 is a side elevation, partly in section, showing in strong lines the condition after the yarns have been threaded through the several holes and weighted, and before the intermediate plates have been shifted into the middle position. The dotted lines show the position of the intermediate plates after they have been shifted into the middle position. Fig. 2 shows the same after the string or wire has been put around the whole mass of yarns between the intermediate plates and the inter-

mediate plates moved apart and the embracing-string tightened and tied, the close-fitting yoke applied and moved downward a little, and the bunch tied again. Fig. 3 is a plan view of one of the plates. Fig. 4 is a plan view of the yoke on a larger scale. Fig. 5 is a horizontal view of the same. Fig. 6 is an elevation of the upper portion of one of the weights, these weights being long and slender and peculiarly hook-shaped to facilitate their attachment to the yarn. Fig. 7 is a view, partly in section, quartering to Fig. 6. Fig. 8 represents a quantity of the material after it has been completely bunched and bound together. Fig. 9 is an edge view, and Fig. 9^a a face view, showing one of the pieces after the bunch has been cut up into short lengths.

Similar letters of reference indicate like parts in all the figures.

20 A is a table or fixed support, having a sufficient aperture to allow the hooked wires or slender weights to depend therein at a little distance apart, as required by the plates.

A' is an upright, supported by the table 25 forming a portion of the rigid frame-work.

B' B² B³ B⁴ are horizontal plates, of brass or other suitable material, having thickly-set perforations b, the perforations in all these plates corresponding perfectly, so that when two or 30 more are brought close together needles or other guiding means conducting the several yarns may be extended at one operation through a number of the plates.

C are brackets, to which these plates are 35 attached, and by which they are held at various elevations on the upright A' by means of clamping-bolts c and thumb-nuts c'.

D are slender weights, made of stout wire or other suitable heavy material, hook-formed at their upper ends, and attached one 40 to each of a set of independent yarns or threads, d, extending from spools above. (Not represented.)

E is a yoke, made in two halves and connected by screws e.

G are slender straps, by which two or 45 more parallel plates may be held together, and H are the bolts and nuts by which the parallel plates are confined to the several 50 brackets C, as required in the several changes. Other fastenings may be substituted for these, if desired.

In operating the invention, the lower plate, B⁴, is firmly clamped a little above the table 55 A, and the plates B' B² B³ are brought close together in an elevated position and firmly clamped. Then, by any suitable guiding means, the several yarns d are successively extended or rove through the several holes, 60 taking care to introduce the proper colors and shades in the right position. The position of these may be guided by previously picturing upon the uppermost plate. Needles or other suitable devices may be extended through the 65 several holes b, to facilitate the rapid and correct passage of the several yarns d through the

same. After each yarn d has been rove through the proper hole in the three upper plates, B' B² B³, they are extended downward through the lower plate, B⁴, and rove through the corresponding hole therein. It is then attached to a weight, D, and left extended by the gravity of the weight, the gravity being resisted and the yarn held extended by a friction on the spool. (Not represented.) Any suitable let-

70

75

off means may be substituted for friction. It will be observed that the series of holes in the plates B is approximately circular; also, that there is a series of larger holes arranged at a little distance around the exterior. These

80

larger holes may receive a coarser or different set of yarns, or the yarns in these holes may be of the same or finer material; but I prefer, for economy of time, to extend ten or other considerable number of the yarns through

85

each of these outer holes. All these may be attached to a single weight; but the weight should be considerably heavier. The condition now described is shown in the strong lines in Fig. 1. Next the intermediate plates, B² B³, 90

90

are shifted in position by moving downward the brackets C, on which they are supported, and are slackened apart a little by relaxing the bolts H. Next a smooth string or wire, I, (see Figs. 1 and 3,) is extended around the

95

mass of yarns d between the plates B² and B³, and the ends gently stretched to contract the mass. Now the plates B² and B³ are slowly separated, the bolts H being taken out and the

100

bracket C being lowered to allow this movement. In the separation of these plates, B² is moved slowly upward and B³ is moved slowly downward. As the movement progresses a gentle tension imparted by the hands or otherwise to the string or wire I draws the mass

105

of yarns d gradually closer and closer together. These movements progress until the several yarns are compacted solidly together by the tightening of the encircling means I, after

110

which it is firmly and finally bound by a tie, j, of the same or of different thread. The plate B² is bound up by the straps G in close contact with the upper plate, B', which latter does not move throughout the whole operation. The plate B³ is lowered nearly or quite down

115

to the plate B', and is there allowed to rest. Next a ring or yoke, E, formed of two halves, with a circular and smooth interior, is applied upon the most contracted portion of the mass, and the two parts are secured together by screws

120

e. This yoke E is moved slowly downward, and the ties j applied at intervals of half an inch, more or less, and firmly fastened. When this work has been extended downward as far as practicable, it is moved upward over the mass

125

which has been finished, and the same operation commenced on the yarns which converge from above. As this work progresses on the yarns from above the force is applied by hand or otherwise sufficient to overcome the resistance of the friction or other resisting force on the several spools, and to draw down the sev-

130

eral yarns *d* through the several holes in the plates *B'* *B*³. This may be done constantly or intermittently by hand or machinery, the yoke *E* being correspondingly held, so as to compact the yarns together close above the several points or planes where they are being successively tied. This work may go on indefinitely so long as the yarns *d* hold out, and when the end of one of those leaves its respective spool an attendant may supply a fresh spool and attach the end of the yarn thereon, thus allowing the operation to be continued. The compacted mass of yarns are severed by a sharp instrument. A thin disk 15 with a sharp edge, rapidly revolved, may be useful. I have in my experiments used a straight sharp knife. At some stage the yarns *d* below the lowermost tie, *j*, are cut, and the weights *D* are reserved to be similarly used in starting the operation at some 20 subsequent period with a fresh set of yarns, arranged according to the same or a different pattern.

Modifications may be made in many of the 25 details. The plates may be held and moved by different means. The yoke *I* may be equipped with means for temporary or permanent support. Means may be provided for drawing downward the compacted mass of 30 yarns mechanically. In making short lengths only of the mosaic article, I prefer not to pass the several threads from spools, but to simply use short lengths of thread, tying a knot in the upper end of each, so that when the thread is 35 drawn through the several plates and the

weight applied below the knot in the upper end will be arrested against the uppermost plate.

I claim as my invention—

1. The apparatus for manufacturing thread-mosaic, composed of a table, *A*, and standard *A'*, perforated plates carried on said standard *A'*, and weights *D*, all combined and adapted to serve relatively to each other substantially as and for the purposes herein specified. 40 45

2. The perforated plates *B*² *B*³, arranged intermediate between similar plates, *B'* *B*⁴, in combination with means, as *H*, for locking them together and separating them at will, 50 and with means, as *C c*, for holding them in various positions relatively to the plates *B'* *B*⁴, substantially as and for the purposes herein specified.

3. The yoke *E*, made in halves secured together by suitable means, as *e*, in combination with the cord or wire *I*, and arranged as shown relatively to perforated plates *B'* *B*² *B*³ *B*⁴, so as to hold the several threads in the required positions in the product, substantially 55 as herein specified.

In testimony whereof I have hereunto set my hand, at New York city, N. Y., this 15th day of December, 1882, in the presence of two subscribing witnesses.
